UNITED STATES PATENT OFFICE

2,553,508

AIR CONDITIONER

Fred E. White, Ixonia, Wis., assignor to White
Thermo-Unit Company, Ixonia, Wis., a corpo-
ration of Wisconsin

Application September 30, 1949, Serial No. 118,759

4 Claims. (Cl. 219—39)

1

This invention pertains to air conditioning units for both heating and cooling purposes, and more particularly to an apparatus for controlling temperature of circulating air through contact with a series of either heated or cooled tubes.

The invention has primarily for its object to provide a comparatively simple, inexpensive and highly efficient unit of the foregoing character, in which a fixed volume of water may be heated by one or more electrical units to cause continuous circulation of the water through a series of radiation tubes by thermosiphon action, to heat a forced circulation of air contacting said tubes.

Another object of the invention is to provide thermostatic means for independently controlling operation of the water heating and forced air circulating devices.

Another object is to provide for continuous low heating of a fixed quantity of water when the maximum heating capacity is reduced through thermostatic control, thus insuring constant thermosiphon circulation of low temperature water through the radiation tubes for quick responsive maximum heating action when required.

A still further object is to provide means for automatically maintaining a fixed quantity of water in the radiation tubes.

In addition to the foregoing, other objects will appear as the description proceeds, and while the accompanying drawing illustrates one complete physical form of the invention constructed in accordance with the best mode so far devised, it is to be understood that changes in the precise embodiment of the invention are contemplated within the scope of the appended claims.

In the drawing:

Figure 1 is a vertical sectional view taken on the line 1—1 of Figure 2; and

Figure 2 is a similar view taken substantially on the line 2—2 of Figure 1, with parts broken away.

Referring now more particularly to the accompanying drawing the numeral 1 designates a housing provided with a top closure plate 2. The housing 1 and top plate 2 are preferably fabricated from metal sheets 3 with a thin layer of insulating material 4 interposed between the same. The front of the housing 1 is provided with a hinged door 5 to facilitate access to the interior for maintenance and repair.

The cover 2 is provided with a plurality of outlet flues 21 for reception of the usual ducts (not shown) for distribution of conditioned air to several zones.

2

Secured to the back of the housing 1 is a supply duct 17 communicating with an inlet opening 17' formed in the housing 1 adjacent its lower end. The duct 17 may serve as an air return from conditioned zones or to supply fresh air from any desired source.

Mounted within the housing 1, intermediate its upper and lower ends, is a pair of rectangular spaced water headers 6, connected by a series of radiation tubes 7, arranged in spaced staggered relation to allow circulating of air between the tubes. To facilitate flow of water through the radiation tubes 7, the outer walls of the comparatively thin header panels 6, are domed outwardly at 6' in alignment with the ends of the tubes.

For heating purposes, a pair of tanks 8 are provided, each of which serves one of the headers 6 through a connection 9, providing communication between the tops of the tanks 8 and the upper portions of the headers 6. The lower ends of the tanks 8 are provided with return pipes 10 connected to a T fitting 11, which in turn communicates with a branch pipe 12 through a line 13. The branch pipe 12 is connected with the headers 6 adjacent their lower edges to provide return communication between the headers and tanks. A pipe 14, also connected to the fitting 11, is provided with a hand valve 15, to serve as a drain for the entire water system when desired, or to allow circulation of cold water through the headers and tubes for cooling.

Both of the tanks 8 are provided with conventional electric immersion heaters 16 for the purpose of heating water contained within the tank and causing the same to circulate through the headers 6 and connecting radiation tubes 7, through thermosiphon action.

Mounted within the lower portion of the housing 1, intermediate the inlet and the water circulating system described, is a partition shelf 18 provided with a central opening 19, in which a motor driven impeller 20 is mounted to create a forced circulation of air from the inlet 17' through the radiation tubes 7 and outlet flues 21.

For the fundamental purpose of conditioning air, the elements and arrangement thus far described constitute the salient features of the present invention. However for the most efficient and automatic operation of the present unit, several conventional controls are provided, the function of which will be described in detail.

Water is supplied to the headers 6 and connecting flues 7 through a supply line 22, which communicates with one of the headers 6 through

a nipple 23. Obviously the supply line 22 could be controlled by a conventional hand valve for the purpose of maintaining a fixed quantity of water within the headers 6 and the radiation tube 7. However, to accomplish the foregoing automatically, the supply line 22 and nipple 23 may be connected to a two-way valve 24 provided with a float chamber 25, in which a float 26 is mounted to actuate the valve 24 and provide communication between the supply line 22 and nipple 23 when the water level recedes to a predetermined point within the system. When the system is filled to the desired height, the float 26 rises and by means of the valve 24 cuts off the supply line 22, but provides communication between the nipple 23 and a sight glass 27, the lower end of which is connected to a T 28, in communication with one of the headers 6 through a nipple 29, thus allowing water to circulate through the sight tube 27 and provide visible indication of the condition of the system. A thermometer 30 may be connected to the T 28 to indicate the temperature of the water at all times.

In operation, it is undesirable to circulate air through the housing 1, until such time as the water within the headers 6 and radiation tubes 7 has reached a predetermined temperature. Consequently, a thermostat switch 31 is provided to control operation of the circulating impeller 20. A thermostat tube 31' connected with the switch 31 is extended into the upper portion of the housing 1 intermediate the radiation tubes 7 and the outlet flues 21, to be affected by the temperature of air in the housing.

A simple form of wiring for the electrical elements and controls is illustrated diagrammatically in connection with Figure 1, in which a zone thermostat Z controls one of the electrical immersion heaters 16 through a relay box R and circuit wires a. The thermostat 31 independently controls the impeller 20 by the circuit b also connected with the relay box R to which a line circuit L is attached. The remaining heating element 16 is directly connected to the main circuit L through the lines c, and, therefore, is not affected by the thermostat Z.

Operation

To operate the present invention for heating purposes, the valve 15 in the drain pipe 14 is closed, while the headers 6, radiation tubes 7 and heating tanks 8 are supplied with a fixed quantity of water, through the supply line 22 and which is determined by the float valve 24. As indicated in Figure 2 of the drawing it is preferred to maintain a water level within the headers 6 slightly below the top row of radiation tubes 7 in order to allow for expansion through heating. When the water system is properly supplied the main electric circuit L is closed to actuate the electrical heating elements 16 and heat the water within the tanks 8, causing a thermosiphon action through the water system until a predetermined temperature of air is reached in the upper portion of the housing 1, which then affects the thermostat switch 31 to close the circuit b and operate the impeller 20 to create a forced circulation of air from the duct 17, through radiation coils 7 and outlet flues 21. When the zone temperature reaches a desired degree, the thermostat Z is affected to open the circuit a and cut out the connected heating element, after which the unaffected heating element 16 connected directly with the main circuit L continues in operation to maintain suf-

ficient heat for continued thermosiphon action of water within the system, until such time as the zone temperature drops below the setting of the thermostat Z, which again cuts in the unoperative element, and because of the low temperature constantly maintained by the operative electrical element, quick responsive heating of the water is obtained when the disconnected element is put into operation.

- 10 To facilitate free thermosiphon action of the water within the system, one of the headers is provided adjacent its upper end with a vent fitting V, which prevents creation of low pressure vapor lock or air pockets to oppose such action.
- 15 Should the quantity of water within the system become reduced through evaporation or leakage, the float valve 24 lowers with the water level to again open the two-way valve 24 between the supply pipe 22 and the inlet nipple 23 until the water is replenished. As previously explained the sight glass 27 and thermometer 30 indicate condition of the water in the system at all times inasmuch as a constant circulation of water takes place through the sight glass and fitting.
- 20 25 When it is desired to utilize the present unit for cooling purposes, both the float valve 24 and the drain valve 15 are set to open position to allow continuous circulation of cold water through the headers and radiation tubes, and the thermostat 30 31, which controls the circulation impeller is set accordingly for the desired range of cool air. During cooling the heating element circuits are cut out through setting of the zone thermostat Z and the switch y provided in the circuit c.
- 35 Also, the vent fitting V is closed with a plug v (shown in dotted lines in Figure 2) to prevent escape of cooling liquid.

From the foregoing explanation, considered in connection with the accompanying drawing, it will be apparent that a comparatively simple and highly efficient air conditioning unit has been devised for economical operation and maintenance, and which can be converted quickly for either heating or cooling purposes. Also, the controls provided render the operation automatic and fool-proof, in addition to providing maximum efficiency.

I claim:

1. An air conditioning unit comprising, a housing provided with one or more outlet flues and an inlet flue, a pair of horizontally spaced vertical water headers mounted in said housing intermediate said outlet and inlet flues, a plurality of horizontal radiation tubes connecting said headers, a tank having outlet and return connections with one of said headers, an electric heating element for said tank, a motor driven impeller for circulating air through said housing for contact with said radiation tubes, a thermostat affected by the air temperature within the upper portion of said housing for controlling operation of said circulating impeller, and a room thermostat for controlling said electrical heating element.
- 5 2. An air conditioning unit comprising, a housing provided with one or more outlet flues and an inlet flue, a pair of water headers mounted in said housing intermediate said inlet and outlet flues, a plurality of radiation tubes connecting said headers, a pair of tanks each having outlet and inlet communication with one of said headers, an immersion heating element for each of said tanks, and a room thermostat for controlling one of said electric heating elements.
- 10 3. An air conditioning unit comprising, a hous-

ing provided with one or more outlet flues and an inlet flue, a pair of water headers mounted in said housing intermediate said inlet and outlet flues, a plurality of radiation tubes connecting said headers, a pair of tanks each having outlet and inlet communication with one of said headers, an electric heating element for each of said tanks, a room thermostat for controlling one of said electric heating elements, without affecting the other, and a thermostat affected by the air temperature within the upper portion of said housing for controlling operation of said circulating impeller.

4. An air conditioning unit comprising, a housing provided with one or more upper outlet flues and an inlet flue adjacent its lower end, a pair of water headers mounted in said housing intermediate its upper and lower ends, a plurality of radiation tubes connecting said headers, a pair of tanks each having outlet and inlet communications with one of said headers, an electric heating element for each of said tanks, a room thermostat for controlling one of said electric heat-

ing elements, without affecting the other, a motor driven impeller for circulating air through said housing in contact with said radiation tubes, a thermostat affected by the air temperature within the upper portion of said housing for controlling operation of said circulating impeller, and means for maintaining a fixed quantity of water in said headers and radiation tubes.
